UNITED STATES PATENT OFFICE.

LUCIEN BUCK, OF JAMAICA PLAIN, MASSACHUSETTS, ASSIGNOR TO B. F. STURTEVANT COMPANY, OF HYDE PARK, MASSACHUSETTS, A CORPORATION OF MASSACHUSETTS.

APRON DRIER.

Application filed February 1, 1926. Serial No. 85,102.

The present invention relates to apparatus for drying material and more particularly to that type of drying apparatus known as apron driers in which the material is dried 5 while it is being carried along on a conveyor or apron.

Heretofore driers of this type have been used with light-weight, loose packing material over or through which the drying air 10 has been circulated at low pressure. Where relatively heavy, close-packing material has been sought to be dried on this type of apparatus, difficulty has been experienced not only in properly supporting the heavy 15 weight of the material but in forcing the drying air through the same to remove the desired amount of moisture. As a result it has been the general practice to dry such heavy, close-packing materials in small lots 20 on shelves or trays where they stand exposed for substantial periods of time to the drying air. Such a process is necessarily slow and expensive. Moreover, where a plurality of aprons was employed, these were commonly 25 located in a single chamber so that the material on the several aprons was all subjected to the same circulating flow of air. The proper controlling of the temperature, humidity, and velocity of the air for the different 30 aprons, according to the character of the material, and the stage or degree of dryness attained, was impossible. Furthermore, where the air was compelled to pass progressively through first one apron after another and the material carried thereby, the 35 cumulative resistance was such that the circulation of the drying air was so greatly retarded that the proper drying of the material if attained at all, was secured only by long continued treatment.

It is the object of the present invention to produce a drier of the apron type in which all classes of material may be dried to any desired degree, automatically and continuously, with a minimum of time and expense, and under properly controlled conditions as to temperature, humidity and velocity of the drying air.

To the above ends the present invention 50 consists in the drier hereafter described and more particularly defined in the claims.

The accompanying drawings illustrate what is now considered the preferred form of the invention as embodied in a drying apparatus particularly designed for drying

shoddy rubber, although it is to be understood that the illustrated drier may be used for drying other materials either of a fibrous or solid character, and that the invention may be embodied in other forms and 60 constructions. In these drawings, Figure 1 shows the drier in front elevation; Fig. 2 is an enlarged, longitudinal vertical section of the right-hand end of the apparatus shown in Fig. 1; Fig. 3 is an enlarged front elevation of the receiving portion of the drier, showing the spreading mechanism; Fig. 4 is an end view of the same, partly in vertical, 65 transverse section; Fig. 5 is a vertical, transverse section through the apparatus, 70 showing the top and bottom portions of one of the traveling conveyors and the several air ducts for the supply and return of the drying air and for the discharge of the same into the atmosphere; Fig. 6 is a bottom plan 75 view, showing the perforated construction of the conveyor and the scrapers for removing the siftings from the top of the hot air boxes; Fig. 7 is a top plan view at the end of one of the hot air boxes, showing the perforated construction of the top of the air boxes and the screw conveyor for discharging laterally the siftings delivered by the scrapers; Fig. 8 is a vertical, longitudinal 80 section showing the method of mounting the scrapers on the conveyor; and Fig. 9 is a rear elevation of the apparatus, showing the driving mechanism for the conveyors.

The illustrated drier comprises primarily a series of superposed, underlapping, continuously operating aprons or conveyors. The material is delivered upon one end of the uppermost conveyor and at the other end thereof is discharged by gravity upon the next lower conveyor traveling in the opposite direction, from which it is in turn discharged upon another oppositely traveling conveyor, and so on, the material dropping from one conveyor to another and passing back and forth, first in one direction and 95 then in the other, until finally it is discharged from the lowermost conveyor.

The drying of the material is accomplished by means of currents of hot air delivered through air boxes underlying the upper section of each conveyor and having their top surfaces perforated to discharge the heated air through. The conveyors or aprons are also perforated, and suitable partitions and shields are provided so that air 100 105 110

of the predetermined temperature, humidity and velocity is compelled to pass through the predetermined conveyors and through the material carried thereby.

5 In order to insure an even distribution of material and an even depth thereof over the conveyor or apron, a spreading or raking device has been provided at the receiving end of the apparatus which stirs or rakes the 10 material transversely on the upper or receiving apron, a leveling gage limiting the depth of the material on the apron as it passes into the drier.

Means have also been provided at this portion of the apparatus for collecting and carrying away any liquid or material which may drop through the conveyor or apron adjacent to its receiving end.

The apparatus also includes means for removing from the tops of the air boxes such material as may sift through the perforations in the conveyors during the drying operation; these means comprising scrapers upon the bottom surfaces of the aprons or 25 conveyors which scrape the siftings along the top of the air boxes to their ends where such material falls into a transverse trough in which a screw conveyor is operating to discharge the siftings laterally from the apparatus, whence they are returned onto the 30 next lower apron.

Fans and heating units are provided, together with suitable conduits for supplying heated air to the several air boxes, and re- 35 turning the same for reheating or discharging into the atmosphere, dampers being supplied for controlling the flow of air and suitable indicating and controlling devices for indicating and regulating the temperature 40 and humidity.

All of the apparatus except the receiving end of the top conveyor and the discharge end of the bottom conveyor is enclosed by insulated walls in which removable closures 45 are provided for the purpose of access to the interior of the drier.

Referring now to the drawings, the drier therein illustrated comprises six superposed conveyors or aprons, forming an apparatus 50 of such height that it is located on two floors of a factory. As shown in Fig. 1, the two upper conveyors, together with the fans and heater units, are located on the upper floor 11, while the remaining four conveyors are 55 located directly beneath on the lower floor 12. The upper conveyor 14 receives the moist material at the left-hand end, as viewed in Fig. 1, it being discharged from any suitable source of supply into a hopper 60 15 and thence on to the upper section of the conveyor. As the material moves to the right it comes beneath the spreading mechanism, to be described more in detail later, where it is spread or distributed uniformly 65 and evenly over the conveyor or apron.

A trough or tank 19 beneath the conveyor at this point serves to catch any free liquid or material which may drop through the apron.

After passing the spreader and the trough which are unenclosed, the material on the conveyor passes into the closed-in portion of the apparatus. As it enters the drier, it passes beneath the leveling gage or gate 20 which is vertically adjustable to permit 70 the passage of the desired depth of material on the conveyor, at the same time serving as a closure for this portion of the drier. The conveyor and material upon entering the drier pass over the air box 21 which 75 extends beneath the upper section of the conveyor substantially from one end to the other. The top of this air box is provided with numerous small circular holes 22 as shown in Fig. 7, through which the heated 80 air is discharged directly against the bottom of the conveyor or apron. This also is perforated, being formed with a large number of rectangular openings 23 as shown in Fig. 6, forming a mesh or grid construction to 85 permit the air to pass through and over the material supported on the conveyor.

During the traveling of the material across the drier or conveyor 14, a substantial amount of the moisture is removed, and when the material reaches the right-hand end of the machine it falls by gravity from the upper conveyor 14 to the second conveyor 25, being guided thereon by the inclined guides or chute 26. This second conveyor 25 travels in the opposite direction to the top conveyor 14 and carries the material back to the left as viewed in Figs. 1 and 2, passing over an air box 27 similar to 21.

When the material on this second conveyor reaches the left-hand side of the drier, it is discharged into a hopper 29 and chute 30 extending down through the floor 11, and is delivered on to the third conveyor 32 traveling to the right. It is again subjected to drying action from the air in box 34 and is then delivered successively to conveyors 35, 36 and 37, each having its own air box 38, 39 and 40 respectively. The left-hand end of the conveyor 37 extends beyond the enclosed portions of the apparatus, as shown in Fig. 1, and from the end of this conveyor the fully and uniformly dried material is finally discharged.

The construction of the conveyors or aprons is best shown in Figs. 5 and 6. They comprise a plurality of metallic sections 41 perforated as above described. Each section is formed with spaced cylindrical bearing members 42 at their adjacent edges whereby the sections are pivoted or hinged upon a section of tubing or piping 43 which in turn is loosely mounted upon a shaft 45. This shaft comprises a tube or pipe 46 in 130

the ends of which are fixed the stub shafts 47 having the reduced end portions 48 carrying the rollers 49 and links 50.

Each conveyor or apron is carried upon 5 the flat tracks or rails 52 supported upon the angle irons 53. These irons are mounted upon the uprights 54 of the main structure and upon the horizontal brackets 55 secured to such uprights. Wooden strips 10 56 are provided at the outer edges of the metal track 52 to serve as guides or abutments for the ends of the shafts 47 and thereby prevent lateral displacement of the apron and wearing of the apron chain.

15 These tracks extend nearly to the ends of the apron or conveyor and support both the top and bottom sections. The receiving end of the track is bent downwardly as shown at 58, (see Fig. 2), to insure the proper and 20 easy engagement of the rollers therewith.

The conveyors or aprons are supported at each end upon sprockets of which one is power driven and the other an idler. Thus in the topmost conveyor the left-hand 25 sprocket 61 turns idly with the movement of the apron. These sprockets are provided with teeth 62 which enter between the side bars or links 50 and engage with the rollers 49.

30 Means are provided as is usual in sprocket and chain construction for varying the distance between the sprockets, such means comprising, as shown in Fig. 3, a movable bearing block 64 adjustable in the 35 slotted guide 65 by means of the adjusting screw 66.

The spreading or distributing mechanism for spreading the material uniformly over the first conveyor at its receiving end, comprises 40 two sets of vertical rods or teeth which are moved transversely to the feed of the material by eccentric driving mechanism, the two series being reciprocated simultaneously in opposite directions. This 45 mechanism is best shown in Figs. 3 and 4, the rods 68 being fixed in the bars 69 which are mounted to slide in the guides or bearings 70. The bars are reciprocated by means of the eccentrics 71 set 180° apart on 50 the shaft 72, the eccentric straps 73, and the arms 74 pivotally connected to the vertical arms 75 fixed upon the bars 69. As the shaft 72 is rotated through the gear 76, the bars 69 are reciprocated in opposite directions and the pins or teeth 68 act to spread the material uniformly over the apron, at 55 the same time breaking up any large lumps that may be present.

The leveler gage or gate 20 consists of a 60 vertical section mounted upon the vertical support or channel 54 by bolt and slot connection to provide for vertical adjustment for the purpose of regulating the depth of material on the conveyor.

65 The air boxes for delivering the drying

air immediately beneath each perforated apron or conveyor extend beneath the upper section thereof nearly to its ends. As shown in Figs. 1 and 2 these boxes are deepest at the middle of the drier where they receive their supply of heated air, the depth progressively diminishing towards each end.

In order to compel the heated air discharged from these air boxes to pass through the conveyor and the material carried thereon, means are provided for preventing the escape of air downwardly on each side of the air box or upwardly around the edges of the conveyor. The downward escape of air is prevented by means of the 70 bottom partitions 77 extending from the top of the air box at such side to the side walls of the apparatus. The escape of air upwardly around the sides or edges of the conveyor is prevented by means of the inclined 75 shields 78 secured at the uprights 54 with their outer edges fitting closely the side walls of the apparatus. These shields are also supported intermediate their upper and lower edges by the brackets 80. The free 80 lower or inner edges of these shields are so close to the upper surface of the conveyor if not actually in contact therewith that any substantial escape of air around the sides and over the top of the conveyor is prevented. These shields also serve as guards to 85 prevent the material carried by the conveyor from falling off the sides thereof. These partitions 77 and the air boxes 34, 38, 39 and 40 it will be noted, divide the drier 90 into a plurality of drying chambers, each having its supply of heated air and a single loaded apron passing therethrough.

In order to give access to the interior of the air boxes if occasion should arise either 105 for the purpose of inspection, cleaning, or repair, the removable closures 88 have been provided, each opening into a box and being of sufficient size to permit the passage of a workman.

Heated air is supplied to the boxes from the fans and heaters, all of which for convenience are mounted on the second floor of the installation. As shown in the drawings, three of these heating and fan units are provided, each unit supplying air to two of the boxes. Thus unit 82 supplies heated air to the vertical supply conduit 83 which communicates with the two upper boxes 21 and 27 at their middle. Unit 84 delivers air 115 through its supply conduit 85 to box 34 and the box immediately beneath it, while unit 86 supplies air through its conduit 87 to the two lowermost boxes.

Provision is made for the recirculation of 120 the heated air, or of such portion thereof as is desired, by means of return conduits extending from above each conveyor or apron to its proper heater and fan unit. These return conduits are best shown in Figs. 1 125

and 5. For example, return conduits 89 and 90 return the air to the heater and fan unit 84, while conduits 91 and 92 return the air to unit 86. These conduits, as best shown in Fig. 5, are provided at their ends with short branch conduits 94 which pass through the side wall of the drier and terminate in the downwardly open ends 95. A damper 96 controls the return flow of air through 10 these conduits.

The discharge of air from above the conveyors or aprons into the atmosphere is controlled by means of dampers 98 in the discharge conduits 99, extending through the 15 wall of the drier. By proper regulation of these dampers 96 and 98 the operator can recirculate and discharge the desired amounts of heated air. A supply of fresh air is provided through the inlet 100 in the 20 suction conduit adjacent the fan, the closure 101 for which may be opened by the operator to the desired extent. Suitable indicating devices are provided to show the 25 temperature and humidity of the drying air, such as wet and dry bulb thermometers, indicated at 102.

The devices for removing from the top of the air boxes the finer material which sifts down through the perforated conveyor 30 comprises scraper blades mounted upon the bottom faces of the conveyor, which scrape or push these siftings along the top of the air box to the end thereof, where they fall into a transverse trough or channel in which 35 a screw conveyor is rotating and carries the siftings to the outside of the drier. These scrapers are best shown in Figs. 6 and 8 and comprise a pair of scraper blades 103 of fibre or other suitable material secured to 40 the under side of the conveyor in a somewhat oblique or angular arrangement, with their adjacent ends fastened together and slightly behind, in the direction of travel, their distant ends. These blades are free 45 to move up and down to adjust themselves for slight variations in the level of the top of the air box. The method of mounting these scraper blades is shown in Fig. 8 where an angle iron 104 is riveted to the 50 bottom face of the conveyor and is provided with vertical slots 105 for the bolts which pass through the metal wear strip 106 and the fibre scrapers 103.

These scrapers are spaced at intervals on 55 each conveyor, and the end of the box toward which the conveyor moves is provided with a down-turned edge or lip 107 to provide an easy and gradual engagement of the scraper blades with the top of the box.

60 The opposite end of the box i. e. the end of the box from which the conveyor passes, is provided with a transverse trough 109 (see Figs. 2 and 7), with flaring hopper-like walls 110 and carrying at its bottom 65 the feed screw 111 which is continuously ro-

tated through the sprocket 112 by mechanism which is driven from the adjacent sprocket shaft. The siftings which are scraped along the top of the box by the scraper blades, fall down into the trough 70 109, along which they are carried by the feed screw until they drop into the chute 113 outside the drier. This chute extends downwardly and then inwardly through the wall of the drier and delivers the siftings onto 75 the conveyor or apron next below.

The driving mechanism for the several sprockets of the conveyors is shown in Fig. 9, which is a rear elevation of the drier. The power shaft 115 is driven from any 80 suitable source of power and through the pinion 116 drives the gears 117 and 118 in opposite directions. Sprocket chains 119 and 120 drive the counter shafts 121 and 122 respectively. Counter shaft 121 drives 85 the sprocket shafts 123 and 124 and the intermediate shaft 125 from which is driven the sprocket shaft 126. Counter shaft 122 drives sprocket shaft 127 and intermediate shafts 128 and 129 from which sprocket 90 shafts 130 and 131 respectively are driven.

The drier is enclosed in an insulated casting made in the form of panels and bolted or otherwise secured to the framework of the machine. These panels, as shown in 95 Fig. 5, comprise a thick sheet of insulating material protected on both sides by a thin metal cover.

The operation of the drier is as follows. The shoddy rubber or other material to be 100 dried is delivered into the hopper 15 from which it passes to the upper section of the top conveyor. As the material passes from beneath the hopper it is distributed or spread by means of the spreading mechanism, the larger pieces or lumps being broken up. At the same time any excess of liquid and some of the smaller particles of material drop through the apron and fall 105 into the tank 19.

The material on the conveyor then passes beneath the leveler and enters the closed drier and passes over the perforated upper surface of the air box from which heated air at the desired temperature and humidity is flowing under the action of the heater and fan. There being no escape save through the apron and the material, the heated air passes through them, removing moisture from the material in its passage. Such portion of this air will be permitted to escape into the atmosphere through box 99 as may be required to maintain the proper humidity, the remainder being returned to the heater where it is again heated with additional fresh air and then returned 110 to the air box.

Meanwhile the material has been passing through the drier and when it reaches the right hand end, as the conveyor turns down- 115 120 125 130

wardly around the idle sprocket, is discharged upon the next lower conveyor by which it is carried back through the drier in the opposite direction and again subjected to the action of the drying air. Any material which sifts through the openings will be scraped along the top of the box and finally discharged into the trough and thence by the screw carried to the chute 10 113 by which it is returned to the next apron below.

The material passes back and forth through the drier falling from one conveyor onto the one next below, and in such transfer being thoroughly mixed and turned, with the result that all surfaces and all particles of the material are exposed to the drying air. Finally the material is carried out of the closed drier by the lowermost conveyor and 20 discharged in a uniformly and thoroughly dried condition.

By the above described construction both light and heavy material may be dried continuously, automatically and expeditiously. 25 The use of the perforated metallic conveyor and the tubular supporting members enables heavy weights of material to be carried, and by compelling the air to pass through such conveyor and the material, relatively close-packing material may be thoroughly and uniformly dried. By the continuous removal of any siftings which may pass through the perforated conveyor, clogging or interference with the air supply is 30 avoided and the drier may operate on long stretches without the necessity of being periodically shut down for cleaning.

Since mechanism is provided which not only spreads and distributes the material 40 evenly over the perforated conveyor but which serves also to break up and reduce any large lumps, the drier is enabled to handle the material more efficiently both as to time required and degree of dryness secured.

The division of the device into separate 45 chambers each having its own supply of heated air and its single loaded apron avoids the high cumulative resistances of prior driers where the air passed through one apron after another successively. Furthermore, the temperature, humidity and velocity of the drying air applied to the material at different stages of the drying may be independently varied and controlled to suit the 55 varied conditions at such stages, thereby increasing the speed of drying, insuring the desired quality and rendering the apparatus independent of atmospheric conditions, such as excessive humidity in the summer time.

60 While the present invention has been shown and described in connection with a drier designed primarily for handling a particular material, it is to be understood that it is not limited thereto, but may be used 65 with other materials and the form and ar-

rangement of the parts thereof may vary as may be required without departing from the spirit of the present invention.

Having thus described the invention, what is claimed is:

1. In an apparatus of the character described, the combination with a drying chamber comprising closed sides and a closed top and a bottom having a perforate middle portion and imperforate marginal portions, 70 a perforate traveling conveyor traveling through the chamber above the perforate bottom, shields extending from the sides of the chamber close to the traveling conveyor whereby the air from the perforate bottom 80 is compelled to pass through the perforate conveyor and the material carried thereby, and means for delivering heated air through the perforate bottom.

2. In an apparatus of the character described, the combination with a chamber closed at its sides, of a rail on each side of the chamber, a perforate traveling conveyor, means for supporting the same comprising rolls at each side thereof traveling 90 on said rails, an air box beneath the conveyor and having a perforate top to discharge air against the conveyor, means extending from the sides of the chamber in close proximity to the top of the conveyor 95 to prevent the escape of air around the edges of the conveyor, and means for delivering air to the boxes.

3. In an apparatus of the character described the combination with a traveling perforate conveyor, of an air box beneath the same, a transverse trough at the end of the air box, a screw feed in said trough, and a scraper attached to the bottom of the conveyor to scrape any material which passes 105 through the perforate conveyor from the top of the air box into said trough.

4. In an apparatus of the character described the combination with a plurality of superposed perforate traveling conveyors, air 110 boxes beneath the same, means for removing from the top of the air boxes any material which passes through the conveyors and devices for delivering such material onto a lower conveyor.

5. In an apparatus of the character described the combination with a traveling conveyor, of an air box located beneath the conveyor, and a scraper secured to the bottom of the conveyor to scrape the material from 120 the top of the air box, said scraper comprising a blade arranged transversely of the conveyor, and means for supporting the blade having provision for vertical movement of the same relatively to the conveyor.

6. In an apparatus of the character described the combination with a conveyor, of a scraper mounted on the under side thereof, said scraper comprising two blades obliquely arranged end-to-end with their adjacent ends 130

behind, in respect to the direction of movement, their distant ends, and means for securing the blades to the conveyor having provision for vertical movement of the blades 5 relatively to the conveyor.

7. In an apparatus of the character described the combination with a main chamber, of a plurality of superposed, looped, traveling conveyors, the top and bottom conveyors extending to points outside said chamber for the receipt and the discharge respectively of the material to be treated, partitions in said chamber to form separated drying chambers through which the conveyors 15 carry the material, means for heating the air, conduits for delivering the same to each drying chamber, a return conduit from each chamber to the heating means, an exhaust conduit from each chamber to the atmosphere, and means under the control of 20 the operator for controlling the flow of air through the return and the exhaust conduits of any drying chamber independently of any of the other chambers.

25 8. In an apparatus of the character described the combination with a conveyor having openings therethrough for the passage of air, of devices positioned beneath and spaced from the conveyor and having surfaces adapted to retain any material passing through the conveyor, means for supplying air beneath the conveyor, and scrapers attached to the under surface of the conveyor 30 for scraping the material from said surfaces to permit access of the air to the conveyor.

35 9. In an apparatus of the character described the combination with a chamber having a perforate conveyor spaced above the

bottom of the chamber, means for supplying air to the chamber, a scraper mounted upon the bottom side of the conveyor and engaging the bottom of the chamber, means adjacent the end of the chamber to discharge the scraped material laterally of the conveyor. 40

45 10. In an apparatus of the character described the combination with a plurality of drying chambers of a plurality of superposed underlapping perforate traveling conveyors passing through the drying chambers, an air box beneath each conveyor having a perforate top to permit the discharge of heated air through the perforate conveyor, each air box having an imperforate bottom, shields extending from the top of each air box to 50 the sides of the chamber, the top of the drying chamber for the conveyor immediately below comprising said imperforate bottom and said shields, and means for supplying heated air to the boxes. 55

60 11. In an apparatus of the character described the combination with a chamber closed at its sides of a rail on each side of the chamber, a perforate traveling conveyor, means for supporting the conveyor comprising rolls at each side thereof traveling on the rails, an air box of less width than the conveyor arranged beneath the conveyor and adapted to discharge air upwardly against the conveyor, means for delivering air to the 65 air box, and shields extending from the sides of the chamber in close proximity to the top of the conveyor to prevent escape of air around the edges of the conveyor. 70

In testimony whereof I have signed my name to this specification.

LUCIEN BUCK.
